UNITED STATES PATENT OFFICE

167,552

TOY ELEVATOR

Lewis A. Baumann, Thor, Iowa

Application April 9, 1952, Serial No. 19,260

Term of patent 14 years

(Cl. D34—15)

To all whom it may concern:

Be it known that I, Lewis A. Baumann, a citizen of the United States of America, residing at Thor, in Humboldt County, State of Iowa, have invented a new, original, and ornamental Design for a Toy Elevator, of which the following is a specification, reference being made to the accompanying drawing, forming a part thereof:

Fig. 1 is a perspective view of the top and one side of the toy elevator, showing my new design; and Fig. 2 is a perspective view of the top and the other side thereof.

I claim:

The ornamental design for a toy elevator, as shown.

LEWIS A. BAUMANN.
